CLAIM

The ornamental design for a cordless reciprocating saw, as shown.

DESCRIPTION

FIG. 1 is a perspective view of a cordless reciprocating saw; FIG. 2 is a top plan view thereof; FIG. 3 is a bottom plan view thereof; FIG. 4 is a right side elevational view thereof; FIG. 5 is a left side elevational view thereof; FIG. 6 is a front elevational view thereof; and, FIG. 7 is a rear elevational view thereof of the present invention.

The broken lines showing environment in the drawings are for illustrative purposes only and form no part of the claimed design.
